ELLIS W. COOPER, OF BLOOMFIELD, NEW JERSEY, ASSIGNOR TO R. HOE AND CO., OF NEW YORK, N. Y., A CORPORATION OF NEW YORK.

METHOD OF AND APPARATUS FOR CASTING CURVED PRINTING-PLATES AND THE LIKE.

1,028,330.

Specification of Letters Patent.

Patented June 4, 1912.

Application filed October 22, 1910. Serial No. 588,449.

To all whom it may concern:

Be it known that I, ELLIS W. COOPER, a citizen of the United States, residing at Bloomfield, county of Essex, and State of New Jersey, have invented certain new and useful Improvements in Methods of and Apparatus for Casting Curved Printing-Plates and the Like, fully described and represented in the following specification and 10 the accompanying drawings, forming a part of the same.

This invention relates to certain improvements in methods of and apparatus for producing curved printing plates, and has 15 been designed especially for use in casting the backing on curved electrotype plates.

Some printing plates, particularly electrotype plates, are very thin and, before they can be used on the cylinders of the 20 printing machine for printing purposes, it is necessary that a backing be formed on them to enable them to withstand the printing operations. In producing curved electrotype plates ready for the printing operation, 25 the present practice is to cast this backing on the electrotype plate in a flat mold, and when the mold has set, to bend the electrotype plate and its backing to curved or similar form. This method has many serious 30 defects and disadvantages, especially on account of the unequal stretching of the metal during the bending operation. This unequal stretching results in a lack of register, which is particularly objectionable in color 35 printing, where a considerable number of different impressions are made on the same sheet, and slight differences in register ruin the product. Many attempts to avoid this mode of procedure have been made, the 40 method having been attempted of casting the backing on the electrotype plate in molds curved to the cylindrical form desired. This attempt proved impracticable, however, on account of the liability of the metal 45 forming the backing to flow in over the face of the electrotype, and, furthermore, on account of the backing being formed of different densities there resulted a distortion of the face of the electrotype plate or unequal 50 pressure in printing.

The present invention has for its object to obviate the disadvantages referred to, and consists in a novel method for casting the backing on curved printing plates, particu-

larly electrotype plates, by which the backing is cast so that it is uniformly distributed over the back of the plate and has a uniform density. These results are obtained by casting the backing metal on the plate in a rapidly rotating mold, so that the backing 55 is deposited and distributed by the action of centrifugal force.

A convenient apparatus for carrying out the method and which forms part of my invention, consists of a hollow drum having a removable cover to permit the insertion and withdrawal of the plate or plates to be backed, with means for rotating the drum. Suitable means, such as clamps, having surfaces which will not stop the flow of the metal past them, are provided to hold the edges of the plate or plates and secure the same in position in the drum. The means for rotating the drum must be such that the speed of the drum will be sufficiently high 60 to obtain the desired action of centrifugal force, this speed depending somewhat upon the size of the drum, any speed securing 65 such centrifugal force as to deposit and distribute the metal so that it has a uniform 70 density being sufficient. In carrying out the invention, a number of plates, covering substantially the entire inner surface of the drum, preferably are backed at one operation, the edges of the plates being secured 75 in place by the securing means, as clamps. The drum preferably is first run up to working speed, then a charge of the backing 80 metal introduced, and the drum rotated until the backing has set. A continuous backing 85 is thus formed on the back of the plates, the clamps preventing metal from being deposited on the face or printing surface of the plates. The cover of the drum is then removed, and the continuous plate thus formed 90 is cut out or otherwise separated into sections for the different plates and trimmed for use. Of course, if desired, it is obvious 95 that a plate or plates covering less than the whole of the inner surface of the drum may 100 be operated on. In such case suitable filling blocks or plates may be employed, covering that portion of the inner surface of the drum not covered by the plate or plates. Such an apparatus of simple form is shown 105 in the accompanying drawings, in which—

Figure 1 is a side view, partly in section, of the drum and the means for supporting

and driving it; Fig. 2 is an end view of a portion of the drum, showing the means employed for securing the cover of the drum in place; Fig. 3 is a view, partly in section, of 5 a portion of the drum showing the clamps employed for securing the plate or plates in the drum.

Referring now to these drawings, 1 indicates a suitable bed or support on which 10 is mounted in bearings 2 the shaft 3, which, in the construction illustrated, supports the drum, and by which the drum is driven through any suitable driving means, as pulley 4. The drum 5 is a hollow drum, and 15 is formed with a hub 6 on shaft 3, the drum being secured to the shaft 3 so as to rotate therewith by a feather 7. A removable open cover 8 is provided which covers one face of the drum and acts to hold the back- 20 ing metal in the drum, while it is being cast on the plate. The means for securing this cover in position may be varied. As shown, the cover has a flange 9 adapted to abut against a shoulder 10 formed on the drum. 25 The flange 9 is held against this shoulder by screws 12 in locking arms 13 pivotally supported on studs 15, mounted in a flange 16 on the drum.

As before indicated, clamping means are 30 provided for securing the plate or plates in the drum so that the metal will not work around on to the outer or printing surface of the plate. In the preferred construction, these securing means are in the form of 35 clamps 17, which overlap the meeting edges of two plates and extend the width of the plates and which preferably have inclined surfaces, as indicated in Fig. 3, permitting the flow of metal past them. These clamps 40 are held in clamping position and released therefrom by bolts 18 passing through the walls of the drum and act to hold the edges of the plates together and prevent metal from working between the edges of the 45 plates and getting on the printing surface thereof. As before stated, a number of plates are preferably backed at one operation, a plate *a* and a portion of two other plates *b*, *c*, being shown in Fig. 3 secured 50 in the drum by these clamps 17. A charge of stereotype metal, which is to form the backing of the plate, is introduced into the drum, preferably while the latter is rotat- 55 ing. To this end the cover of the drum is formed with a central opening, as shown in Fig. 1, and extending into the drum through this opening, is a supply pipe 19, arranged so that its delivery orifice is substantially central of the drum.

60 If desired, a heating means may be provided, such as a gas pipe 20, suitably located below the drum, to heat the drum so as to avoid any sudden chilling of the metal when introduced.

65 Preferably in this method of casting, the

plate or plates are bored or shaved out to uniform thickness while in the drum after the backing metal has set, it being obviously possible by any suitable tool or machine (not shown) to rough out the backing formed 70 throughout the entire surface of the drum.

It will be understood that the apparatus employed for carrying out the method is not limited to that shown and described, but that changes and variations may be 75 made in the same without departing from the invention.

What is claimed is:—

1. The method of casting a backing on curved printing plates which consists in securing a plate in a mold and introducing molten metal which is to form the backing of the plate into the interior of the mold, and rotating the mold at a speed sufficient to distribute the metal by centrifugal action 85 against the inner surface of the plate until the metal has set.

2. The method of casting a backing on curved printing plates which consists in securing a plate in a drum and introducing molten metal which is to form the backing of the plate into the interior of the drum and rotating the drum at a speed sufficient to distribute the metal by centrifugal action 90 against the inner surface of the plate until 95 the metal has set.

3. The method of making curved printing plates which consists in securing a plurality of curved plates in a mold, introducing molten metal which is to form the backing 100 of the plates into the interior of the mold, rotating the mold at a speed sufficient to distribute the metal by centrifugal action against the inner surface of the plates until the metal has set, and separating the continuous plate so formed into the different 105 plates.

4. The method of making curved printing plates which consists in securing a plurality of curved plates in a drum, introducing 110 molten metal which is to form the backing of the plates into the interior of the drum, rotating the drum at a speed sufficient to distribute the metal by centrifugal action against the inner surface of the plates until 115 the metal has set, and separating the continuous plate so formed into the different plates.

5. In an apparatus for making curved printing plates, the combination with a mold 120 of means for removably securing a curved printing plate in the mold, and means for rotating the mold to deposit a charge of molten metal introduced therein on the back of the plate.

6. In an apparatus for making curved printing plates, the combination with a mold of means for removably securing a plurality of curved printing plates in the mold, and means for rotating the mold to deposit 130

- a charge of molten metal introduced in the mold on the back of the plates. 35
7. In an apparatus for making curved printing plates, the combination with a mold and means for rotating it, of means for removably securing a plurality of curved printing plates in the mold, means for introducing molten metal in the mold, and means for heating the mold. 40
- 10 8. In an apparatus for making curved printing plates, the combination with a mold and means for rotating it, of means for removably securing a plate in the mold so that its face is next the inner mold walls, 45
- 15 means for introducing molten metal into the mold, and means for preventing the molten metal from coming into contact with the face of the plate. 50
9. In an apparatus for making curved 55
- 20 printing plates, the combination with a drum and means for rotating it, of means for introducing molten metal into the drum, and means for securing a plate in the drum so that the face of the plate is next to the inner wall thereof and for preventing molten metal from coming into contact with the face of the plate. 60
10. In an apparatus for making curved printing plates, the combination of a drum 65
- 30 having a cover, means for rotating the drum, means for introducing molten metal into the drum, means for clamping a plate in the drum so that its face is next to the inner wall thereof and for preventing the molten
- metal from coming into contact with the face of the plate, and means for removably securing the cover to the drum. 35
11. In an apparatus for making curved printing plates, the combination with a mold and means for rotating it, of clamps for securing plates in the mold so that metal introduced in the mold will not come in contact with the face of the plate. 40
12. In an apparatus for making curved printing plates, the combination with a drum and means for rotating it, of clamps overlapping the meeting edges of two plates and extending the width of the plates for securing the plates in the drum and preventing metal introduced into the drum from coming in contact with the faces of the plates. 45
13. In an apparatus for making curved printing plates, the combination with a drum and means for rotating it, of clamps having curved surfaces overlapping the meeting edges of two plates and extending the width thereof for securing the plates in the drum, and preventing metal introduced into the drum from coming in contact with the faces of the plates. 50

In testimony whereof, I have hereunto set my hand, in the presence of two subscribing witnesses.
